(57) **CLAIM**

The ornamental Design for seating elements of a modular seating furniture, as shown and described.

DESCRIPTION

FIG. 1 is a front perspective view of seating elements of a modular seating furniture in accordance with the present design; and

FIG. 2 is an exploded view of the seating elements of a modular seating furniture of FIG. 1;

FIG. 3 is a front perspective view of an armrest of the seating elements of a modular seating furniture of FIG. 1;

FIG. 4 is a front view of the armrest of FIG. 3;

FIG. 5 is a rear view of the armrest of FIG. 3;

FIG. 6 is a left side view of the armrest of FIG. 3;

FIG. 7 is a right side view of the armrest of FIG. 3;

FIG. 8 is a top view of the armrest of FIG. 3;

FIG. 9 is a bottom view of the armrest of FIG. 3; and

FIG. 10 is a front perspective view of a backrest of the seating elements of a modular seating furniture of FIG. 1;

FIG. 11 is a front view of the backrest of FIG. 10;

FIG. 12 is a rear view of the backrest of FIG. 10;

FIG. 13 is a left side view of the backrest of FIG. 10;

FIG. 14 is a right side view of the backrest of FIG. 10;

FIG. 15 is a top view of the backrest of FIG. 10;

FIG. 16 is a bottom view of the backrest of FIG. 10;

FIG. 17 is a perspective view of a seat base of the seating elements of a modular seating furniture of FIG. 1;

FIG. 18 is a front view of the seat base of FIG. 17;

FIG. 19 is a rear view of the seat base of FIG. 17;

FIG. 20 is a left side view of the seat base of FIG. 17;

FIG. 21 is a right side view of the seat base of FIG. 17;

FIG. 22 is a top view of the seat base of FIG. 17; and

FIG. 23 is a bottom view of the seat base of FIG. 1.

The broken lines in the Figures illustrate environmental structure are not part of the claimed design.
